to Harris-Seybold-Potter Company, Cleveland,
Ohio, a corporation of Delaware

Application July 22, 1940, Serial No. 346,836

7 Claims. (Cl. 1—11)

The present invention relates generally to a wire stitching or stapling machine, but more particularly to a semi-automatic type tie stitching machine in which a single wire stitching head of the conventional type and a single reel of wire is employed to effect a tie stitch of the form in which the first two and last two staples in each article to be stitched such as a box blank are placed in close proximity with respect to each other while the intervening staples are spaced apart at normal pre-determined intervals.

One of the objects of the invention is to provide a novel and improved tie stitching mechanism in which the conventional stitcher head may be employed so as to automatically effect a differential spacing between certain of the staples in each box blank.

A further object of the invention is to provide a novel and improved stitching mechanism in which a single conventional type stitcher head may be employed to secure a differential spacing or interval between the stitches or staples in the box blanks and also having means associated therewith whereby the spacing between the staples may be adjusted so that any pre-determined number of staples may be inserted in the box blank.

A still further object of the invention is to provide a novel and improved stitching mechanism in which a single conventional type stitcher head may be employed in combination with associated mechanism so as to effect either a seam of uniformly spaced stitches or one in which the two stitches at each end of the seam are spaced more closely than the rest.

These and other objects are accomplished by providing a construction and an arrangement of the various parts in the manner hereinafter described and particularly pointed out in the appended claims.

Referring to the drawings:

Fig. 1 is a fragmentary top plan view of our improved stitching machine with the stitcher head shown at an angle of forty-five degrees with respect to the main drive shaft;

Fig. 2 is a top plan view of a box blank illustrating one form of the tie stitch in which the staples are arranged at a 45° angle;

Fig. 3 is a similar view of a box blank showing another form of the stitch in which the staples are at right angles to the direction of travel of the box blanks;

Fig. 4 is a similar view of a box blank showing a third form of tie stitch in which the staples are placed parallel to the direction of travel of the box blanks;

Fig. 5 is a cross sectional view taken on the line 5—5 in Fig. 1;

Fig. 6 is a fragmentary cross sectional view taken on the line 6—6 in Fig. 5;

Fig. 7 is a fragmentary front elevational view of our improved stitching mechanism with the stitcher head removed therefrom;

Fig. 8 is a perspective view of our improved tie stitching machine with the stitcher head shown at right angles to the main drive shaft;

Fig. 9 is a cross sectional view taken on the line 9—9 in Fig. 1; and

Fig. 10 is a fragmentary view showing parts of the trip control for the tie stitch mechanism.

In illustrating our invention we have shown the same as comprising a main frame or standard 10 which has the usual horizontal projecting arm 11. Secured to the frame 10 below the arm 11 is the usual work table 12. Journaled in suitable bearings in the horizontal arm 11 is a main drive shaft 13. Loosely mounted on the rear end of the shaft 13 is a drive pulley 14. The pulley 14 is operatively driven by an electric motor (not shown). Positioned between the pulley 14 and the main shaft 13 is a clutch mechanism generally indicated by the reference character 15. This clutch 15 is of any well known form and may be manually or foot controlled, or may be automatically tripped by means located in the path of the articles to be stitched as will hereinafter be more fully described. Secured to the driven pulley 14 is a sprocket wheel 16. Mounted in the bearing bracket 17 secured to the main frame 10 is a stub shaft 18. Secured to the outer end of the stub shaft 18 is a sprocket wheel 19. The sprocket wheel 19 is geared to the sprocket wheel 16 by means of a chain 20. Secured to the shaft 18 adjacent the sprocket wheel 19 is a gear 21. Journaled in the bracket 17 above the stub shaft 18 is a longitudinally extending shaft 22. The shaft 22 is driven by a gear 23 which in turn meshes with the gear 21. The other end of the shaft 22 is provided with two continuously driven spaced apart kick-out rollers 24, which are located below, but protrude slightly above the table as clearly disclosed in Figs. 7 and 8 of the drawings. The table 12 is supported on and above a horizontally disposed frame member 25 which has its inner ends secured to the vertical standard 10 of the main frame. The outer end of the shaft 22 is journaled in a bearing 26 of a bearing bracket 27. Spaced rearwardly from the bearing 26 and formed integrally with the bracket 27 is a second bearing 28 in which an intermittently driven shaft 29 is journaled. Secured to the shaft 29 and in alignment with the continuously driven rolls 24 are horizontally spaced apart intermittent feed or conveyor rolls 30. The inner end of the intermittently driven shaft 29 is provided with a gear 31, which in turn, is operatively driven by a gear 32 secured to a shaft 33. The outer end of the shaft 33 is journaled in the bearing bracket 17. The intermittent motion is transmitted to the shaft 33 from the main drive

shaft 13 by the mechanism that will hereinafter be more fully described. Meshing with the gear 31 is a gear 34 which in turn, is secured to a stub shaft 35. Connected to the shaft 35 by means of flexible or universal joint 37 is a flexible shaft 37'. The outer end of the shaft 37' is connected by means of a flexible joint 38 to a shaft 39. The shaft 39 has its opposite ends journaled in spaced apart arms 40 which in turn, have their intermediate portions pivoted on pins 41. The pins 41 are secured to fulcrum brackets 42. The fulcrum brackets 42 are secured to the oscillating shaft 43. The shaft 43 is journaled in spaced apart bearings 44 of a bearing bracket 45 which is secured to the horizontal arm 11 of the main frame. Positioned in vertical alignment with the intermittent conveyor rollers 30 are complementary spaced apart upper feed rollers 46 which are secured to the intermittently driven shaft 39. The rollers 46 are yieldingly pressed into engagement with the box blanks passing thereunder by means of springs 47. Journaled in the rear end of the bearing brackets 42 is a shaft 48. Located in vertical alignment with the continuously driven discharge or kick-out rollers 24 and secured to the shaft 48 are idle rollers 49. The outer end of the shaft 43 is journaled in a bearing bracket 50 which in turn is secured to the main frame member 10 in any well known manner. Secured to the shaft 43 adjacent the bearing 50 is a rocker arm 51. The free end of the rocker arm 51 is provided with a roller 52 which is located in the path of and adapted to be engaged by an eccentric cam 53 which in turn is secured to the main drive shaft 13.

From the above description it will be obvious that when the article to be stitched such as a box blank is inserted so as to engage the trip hereinafter described, said trip will automatically engage the clutch which operates the main drive shaft 13 to revolve the cam 53. The cam 53 during its cycle of operation, will then engage the roller 52, thereby rocking the shaft 43 and its associated brackets 42 and arms 40 so as to lower the intermittently actuated feed rolls 46 and thereby press the box blank between these rollers and the lower intermittently driven feed rollers 30. Secured to the inner end of the shaft 43 is a clutch control lever 54 which is adapted to keep the clutch in driving operation with the main drive shaft when the intermittently acting feed rollers are feeding the box blanks to the machine for spacing the staples.

Located in an opening in the table 12 and in the path of the incoming box blank is a vertically movable clutch throw-out trip control member 55 which has its lower end secured to a horizontally movable bar 56. The bar 56 is pivotally connected to parallel links or arms 57 and 58. The link 58 is secured to a shaft 59. The shaft 59 is journaled in a bearing formed in the supplemental frame member 60 which in turn is secured to the frame member 25. The link 57 is pivoted on a pin 61 mounted in the outer end of the bracket 60. Secured to the inner end of the shaft 59 is an arm 62, the free end of which is connected to the lower end of a pitman 63. The upper end of the pitman 63 is pivotally connected to the free end of an arm 64. The arm 64 is secured to a stub shaft 65 which is journaled in a bearing bracket 66 which in turn is secured to the main frame or standard 11. Secured to the inner end of the stub shaft 65 is a depending arm 67. The free end of the arm 67 is connected to a slotted link 68. Pivoted to a pin 69 mounted

in the bracket 66 is a gravity or spring actuated clutch locking lever 70. The link 68 is provided with a slot 71 which loosely engages the pin 72 secured to one side of the clutch locking lever 70. The lower end of the locking lever 70 is provided with a locking notch 73 which is adapted to engage a roller 74 which is journaled on the free end of the rocker arm 51.

From the above description it will be seen that as the box blank is moved into the position beneath the stitching mechanism it engages a trip clutch hereinafter described, so as to actuate the clutch into engagement with the main drive shaft. In this connection it will be noted that the incoming box blank will depress and hold the throw-out trip 55 in its lower position. At this instant the roller 74 on the rocker arm 51 will ride downwardly along the forward edge of the clutch locking lever 70 so that when the cam 53 actuates the cam roller 52 and rocker arm 51 downwardly, the roller 74 will engage the notch 73 of the clutch lock-out lever 70 so as to maintain the intermittently actuated feed rolls 46 and 30 in engagement with the box blank located therebetween. In this connection it will also be noted that as the rear end of the box blank passes the trip 55, the mass or weight of pitman 63 will return the strip 55 to its upper position and will swing the clutch locking lever 70 outwardly to disengage the notch 73 from the roller 74, thereby permitting the rocking arm together with the intermittent feed rolls to separate, at the same time releasing the lever 54 to actuate the clutch mechanism and disengage it from the main drive shaft 13 of the stitcher head. In this connection it will also be noted that as the rocker arm 51 is raised, by spring 51' and arm 52' the idle rollers 49 will be depressed toward the rear continuously driven kick-out rollers 24 to discharge the box blank rearwardly of the machine. A conventional form of braking mechanism generally indicated by the reference character 33' is provided for stopping the intermittently driven roller at the conclusion of each movement.

The mechanism hereinbefore described constitutes essentially the conventional operative parts which are essential to the function and operation of our improved tie stitching machine. One of the essential features of this novel improvement includes the employment of a single conventional stitcher head, a single wire reel and associated adjusting mechanism which permits the stapling of box blanks so as to effect automatically the insertion of staples at different predetermined intervals, thereby permitting a tie stitch at both ends of the box blank. The tie stitch in the present instance permits the stapling of the two successive staples at the beginning and the end of the box blank in relatively close proximity while the intermediate staples are inserted at uniform and relatively larger intervals. In this connection it will be noted that certain adjusting mechanism is provided whereby these intervals may be varied both in the tie stitch and in the intermediate stitches. A clearer understanding of the operation of the tie stitch can be had by referring to Figs. 2, 3 and 4 of the drawings, in which are shown staples in box blanks where the staples proper are angularly disposed with respect to the direction of travel of the box blanks or are arranged parallel to the direction of travel of the box blanks as shown in Fig. 4 of the drawings.

Our improved type of stitching mechanism contemplates the employment of a conventional

type stitcher head, in this case generally indicated by the reference character 16. The stitcher head 16 in this instance, as shown in Fig. 1 of the drawings, is located at an angle of substantially 45° with respect to the main drive shaft 13, but it is quite obvious that the same may be placed at right angles thereto as shown at 76 in Fig. 8 of the drawings, or at any angle with respect to the main drive shaft. In order to drive the stitching head mechanism of the conventional construction from the main drive shaft 13, miter gears 17 and 18 as shown in Fig. 1 of the drawings, are employed. The staple forming and driving mechanism and operative parts associated with the stitcher head are conventional in every respect and for that reason it is believed that a further detailed description is unnecessary. Secured to the rear end of the main drive shaft 13 is a driven disc 79. Attached to the disc 79 is a cam disc 80. The disc 79 is provided with a radially disposed T slot 81. Adjustably mounted in the T slot 81 is a block 82. Mounted in a radially disposed threaded bore 83 in the block 82 is a threaded bolt 84. The bolt 84 is provided with a shoulder or annular collar 85 formed integrally therewith and spaced from the head of the bolt so as to form a shoulder to be engaged by transverse plate 86 which in turn is secured to the disc 79 in any well known manner. Protruding outwardly from the block 82 is a pin or stud 87 on which is pivoted the upper end of a pitman 88. The lower end of the pitman 88 is connected through the medium of a pin bolt 89 which in turn is secured to a ratchet pawl arm 90. Secured to the shaft 33 adjacent its inner end is a ratchet wheel 91, which in turn is provided with a hub 92. The pawl arm 90 is journaled on the hub 92 of the ratchet wheel. (See Fig. 6 of the drawings.) Pivoted on a pin or bolt 93 on the free end of the arm 90 is a ratchet pawl 94. Secured to the bracket 17 in any well known manner is a bracket 95. Formed integrally with the bracket 95 is an angularly disposed block 96. The block 96 is provided with a rectangularly shaped and angularly disposed slot 97 in which a bar 98 is slidably mounted. Secured to the upper end of the post or bar 98 by means of machine screws 99 is a ratchet shield 100. The shield 100 has a longitudinally extending slot 101 which is adapted to embrace the shaft 33 so as to permit the shield to be lowered or raised with respect to the ratchet wheel 91 in the manner hereinafter described. The shield 100 is provided with a sector or fan-like section 102. The sector-like section 102 of the shield 100 is of an arcuate shape whose periphery in raised position projects slightly above the periphery of the teeth of the ratchet wheel 91 so as to be in a position to engage a laterally projecting portion 103 formed on the free end of the pawl 94 to hold the pawl out of engagement with the ratchet teeth of the ratchet wheel 91 during certain operations of our tie stitching machine. In this connection it will be noted that if the operator is desirous of effecting a normal stitching operation and eliminating the tie stitch, the same may be accomplished by locking the shield 100 in any manner in its lowermost position so that full stroke of the pitman 88 may be employed there by permitting the pawl to engage the ratchet wheel teeth during its full stroke. In this connection it will also be noted that a variation in the interval or space between the adjacent stitches may be accomplished by adjusting the

bolt 84 so as to vary the position of the pin 87 from the center of the drive shaft or disc 79, thereby permitting the normal interval between the staples to be set at any pre-determined distance.

In order to effect the tie stitch or two stitches at closer intervals at the beginning and the end of each box blank and also provide means for varying the intervals between a tie stitch and an adjacent regular stitch, we have provided a supplemental or an adjustable shield extension 104. The shield extension 104 has an arcuate portion co-extensive with that of the shield 100 and is provided with a circular opening 105 which engages an annular flange or hub 106 formed integrally with the shield 100. The shield 100 is provided with an arcuate slot 107 through which a bolt 108 is adapted to extend. The bolt 108 has its lower threaded portion adapted to engage a threaded aperture 109 located in the adjustable shield 104. From the above it will be quite obvious that the shield extension 104 may be adjusted or rotated with respect to the shield 100 and fastened in various positions of adjustment with respect thereto by tightening the bolt 108. It will be noted that the amount of the movement of the ratchet wheel 91 imparted by the pawl 94 is determined by the position of the shield 104 with respect to the shield 100. In other words, the effective stroke of the pitman 88 imparted to the pawl 94 is controlled by the adjustment of the shield extension 104 with respect to the shield 100 so that if the operator is desirous of adjusting or changing the intervals between the first two and the last two staples inserted in a box blank, the same may be effected by adjusting the shield extension 104 with respect to the main shield 100. It is quite obvious from the above that when the ratchet shields 100 and 104 are held in their downward position, the normal full stroke of the pawl 94 is imparted to the ratchet wheel which in turn imparts its motion to the intermittently driven upper and lower feed rolls 46 and 30 for properly spacing the intermediate staples at uniform intervals, dependent upon the distance at which the pitman pin 87 is set with respect to the driving disc 79.

The actuation of the ratchet shield is controlled automatically by the travel of a box blank through the machine for effecting a tie stitch at the end of the seam of that blank and at the beginning of the seam of the next succeeding blank. This mechanism includes a vertically movable tie stitch trip or gauge 109 mounted in an opening in the table 12 and in the path of the box blanks. This trip 109 has its lower end rigidly secured to a horizontal bar 110. The horizontal bar 110 is pivotally mounted on parallel links 111. One of the links 111 is pivoted on a pin 112 carried by the supplemental frame 60. The other link 111 is secured to a shaft 113 which in turn is journaled in a bearing in the supplemental main frame 60. Rigidly secured to the shaft 113 is a downwardly extending arm 114. The lower or free end of the depending crank 114 is connected by a pitman 115 to the free end of a second depending crank 116. The crank 116 is secured to a shaft 117 journaled in a bearing in the bracket 95. Secured to the shaft 117 and extending at an inclined angle and upwardly with respect thereto is a crank 118. The upper or free end of the crank 118 is pivotally connected as shown at 119 to a link 120. The link 120 is provided with a longitudinally extending slot 121. The slot 121 of the link 120 embraces a

pin 122 of a shield locking plate 123. The shield locking plate 123 is journaled upon a reduced diameter portion 124 of a hub or collar 125 which embraces the shaft 33. The free end of the shield locking plate 123 is provided with a semi-circular locking notch 126 which is adapted to engage a pin 127 which in turn is secured to the shield bar 98 and projects laterally on both sides thereof, as clearly shown in Fig. 6 of the drawings. The shields 104 and 100 together with their supporting or reciprocating bar 98 are held in their uppermost position by a spring 128 which has its upper end as shown at 129 connected to the bearing bracket 95 and its lower end as shown at 130 connected to a pin 131 secured to the lower end of the bar 98. The tie stitch trip is raised to its normal elevated position in the path of the oncoming box blank by means of a spring 132 which has its lower end connected to the free end of the crank 114 and its upper end connected as shown at 133 to the bracket 95. Pivotedly connected as shown at 134 to the bracket 95 is a bell-crank member 135. This bell crank member 135 has a downwardly curved and offset arm as shown at 136 and the lower or free end of this arm as shown at 137 moves in the path of and is adapted to engage one side of the pin 127 carried by the shield bar 98. The bell-crank 135 is provided with an upwardly extending arm as shown at 138. Journaled in the upper end of the arm 138 is a roller 139. The roller 139 is located in the path of and is adapted to be engaged by a cam 140 formed on the periphery of the cam plate 80 for controlling the tie stitching mechanism in the manner hereinafter described. Formed integrally with the bell-crank 135 is a horizontally projecting arm 141 which has its free end connected to a spring 142. This spring normally actuates the bell crank in a direction so as to press the roller 139 against the periphery of the cam 80. Located on and projecting through the table top 12 and in the path of the incoming box blanks is a clutch throw-in trip or gauge 141' which is provided with conventional operative connections for controlling the clutch to connect the same with the main drive shaft 13. This type of operative trip and its connections are conventional similar in function and operation to that shown in the Frank E. Lawrence Patent No. 1,708,274, granted April 9, 1929 on Stitching machine and it is therefore thought that a detailed description of the same is unnecessary. It is quite obvious that a manually operated foot treadle may be employed in substitution for this trip gauge if desirable.

The operation of our improved automatic tie stitcher is as follows:

The operator grasps a box blank, places it upon the table 12 and pushes it between guides towards the stitching mechanism. As the blank moves over the table it depresses trip members 109 and 55 in that order. A forward edge of the blank then passes over the stitching anvil into engagement with trip member 141'. At that time the parts are in the condition illustrated in Figs. 5 and 7.

Before the insertion of the blank into the machine trip 109 stood in its upper position because of the action of spring 132, and slotted link 120 occupied a raised position such that the outer end of slot 121 was in engagement with pin 122. The depression of the trip 109 moves the parts to the position of Fig. 5 without any immediate effect upon the pawl guard 102, 104.

Before the trip member 55 was depressed the latch plate 70 was positively held out of latching position by the pin and slot connection 72, 71. The effect of the depression of the trip 55 is merely to move slotted link 68 toward the right so as to leave latch plate 70 free to swing down into latching position. It remains momentarily in the position illustrated however, being held there by roller 74 on rocker arm 51.

Now when the work is caused to push against trip 141' the main clutch is put into engagement and the shaft 13 begins to turn. The trip 141' is of course held depressed by the work during the further travel of the latter through the machine. The first stitch is now driven. While this is occurring cam 53 acts against roller 52 to depress rocker arm 51, which then swings down until the roller 74 at its free extremity enters the notch 73 at the lower end of latch plate 70, permitting that plate to swing by gravity toward vertical position in which it locks the arm 51 down. The depression of arm 51 turns shaft 43 anticlockwise, which throws feed rollers 46 down to press the work against the lower feed rollers 30. As the shaft 43 turns in the manner stated it also swings the arm 54 down into position to hold the main clutch in engagement.

During the time the first stitch is being driven the pitman 83 moves from the broken line position of Fig. 5 to the full line position thereof. Then as the shaft 13 turns through the second half of its first revolution the pawl 94 rides up on its first working stroke, but being held out of engagement with the ratchet wheel teeth by the guard 102, 104 no rotation of shaft 33 occurs until the pawl rides off the guard extension 104. The remaining portion of the working stroke is then effective to impart a short feed movement to the shaft 33 and thence to the feed rollers 46, 30. The work is therefore advanced through a short space, bringing it into position for the second stitch.

The second stitch is taken during the idling or return stroke of pawl 94. During this return stroke also the cam plate 140 on disk 80 swings bell crank lever 135 clockwise, and the free end 137 of this lever forces pin 127 on plate 98 downward, moving pawl guard 102, 104 downward and to the left out of the way of pawl 94. When the pin 127 reaches its lowermost position the latch plate 123 swings down by gravity, causing the notch 126 to engage the pin 127 and hold it in its lowered position. The pawl 94 is then free to engage the teeth of the ratchet wheel throughout its working stroke, and the blank is advanced a full step thereafter in each feed movement until the latch plate 123 is withdrawn automatically under the control of the work itself, as will presently appear.

The driving of stitches and the intermittent action of the feed rollers 30, 46 alternate, thereby forming a seam of evenly spaced stitches, that is beginning with the second stitch driven. During this time bell crank 135 swings back and forth without effect.

Now, when the rear end of the work clears the trip 109, spring 132 acts through link 115 and lever 116, 118 to raise slotted link 120 and exert an upward pull upon pin 122. Then while the roller 139 is riding upon the cam 140, momentarily relieving the parts from the action of spring 128, the link 120 lifts the pin 122 and swings the latch plate 123 upwardly to the position illustrated. Then, as soon as the roller 139 rides down off the cam 140, spring 128 acts to move

the pawl guard 102, 104 upwardly to the right to the position shown in Fig. 5. The next feed stroke will therefore be a short one, bringing the work into position for the final tie stitch.

Shortly after the rear end of the work clears the trip 109 it also clears the trip 55, which results in swinging the latch plate 70 backward away from the roller 74. Then, as the last stitch is being driven, the high part of the cam 53 moves out of engagement with follower 52 and the rocker arm 51 is permitted to swing up under the influence of spring 51'. Thereby the shaft 43 is turned clockwise through a small angle, withdrawing arm 54 to cause disengagement of the main clutch, separating feed rollers 30 and 46 and swinging rollers 49 down to press the blank against the constantly rotating delivery rollers 24. The finished blank is thereby ejected from the machine.

It will be observed that when the tail end of the blank clears the trip 109 the ratchet mechanism is automatically set for a short feed, and that it remains so set until after the first feed movement has been transmitted to the blank next to be inserted in the machine. The movement of the second blank into the machine does not cause the first short feed movement. On the contrary it sets in motion means for disabling the short feed after the second stitch has been taken. Each piece of work therefore as it enters the machine and depresses the trip 109 has a controlling action to cause a shift at the proper time from short feed to regular feed, and as it clears the trip 109 it has a controlling action to shift from regular feed to short feed.

As previously stated provision is made for varying the spacing between regular stitches by shifting the effective crank arm for pitman 88, and varying the length of the short strokes or tie stitch strokes by adjustment of the pawl guard extension 104. If it should be desired to eliminate tie stitches at the ends of the seam, this can be accomplished by merely disabling the trip 109 and its associated parts, that is by removing the trip or the spring 132.

While in the above specification we have described one embodiment which our invention may assume in practice, it will of course be understood that the same is capable of modification and that modification may be made without departing from the spirit and scope of the invention as expressed in the following claims.

What we claim as our invention and desire to secure by Letters Patent is:

1. The combination with a wire stitching machine, a main drive shaft mounted on said frame, a stitching mechanism mounted on said frame and driven by said shaft for inserting staples in box blanks passing thereunder, box blank feeding mechanism including intermittently driven feed rolls mounted on said frame, a ratchet wheel and pawl mechanism driven by said shaft for actuating said feed rolls and advancing said box blanks in a step by step movement, and means actuated by said box blanks for varying the intermittent movement of said feed rolls.

2. The combination with a wire stitching machine, a main drive shaft mounted on said frame, a stitching mechanism mounted on said frame and driven by said shaft for inserting staples in box blanks passing thereunder, box blank feeding mechanism including intermittently driven feed rolls mounted on said frame, a ratchet wheel and pawl mechanism driven by said shaft for actuat-

ing said feed rolls and advancing said box blanks in a step by step movement, means actuated by said box blanks for controlling the intermittent movement of said feed rolls, and means for adjusting said last named means for varying said intermittent movement.

3. The combination with a wire stitching machine, a main drive shaft mounted on said frame, a stitching mechanism mounted on said frame and driven by said shaft for inserting staples in box blanks passing thereunder, box blank feeding mechanism including intermittently driven feed rolls mounted on said frame, a ratchet wheel and pawl mechanism driven by said shaft for actuating said feed rolls and advancing said box blanks in a step by step movement, and a movable member controlled by said box blank for holding said pawl out of engagement with said ratchet wheel to vary the intermittent movement of said feed rolls.

4. The combination with a wire stitching machine, a main drive shaft mounted on said frame, a stitching mechanism mounted on said frame and driven by said shaft for inserting staples in box blanks passing thereunder, box blank feeding mechanism including intermittently driven feed rolls mounted on said frame, a ratchet wheel and pawl mechanism driven by said shaft for actuating said feed rolls and advancing said box blanks in a step by step movement, and a shield of adjustable length positioned adjacent said ratchet wheel and controlled by said box blank, said shield being adapted to engage said pawl for reducing the movement of said feed rolls.

5. In a machine for stitching a seam, stitching mechanism operating at regularly recurrent intervals, intermittently acting feeding means tending to move the work forward a predetermined distance between successive stitches, means tending to shorten the stroke of the feeding means, latch means for holding said stroke shortening means out of operative position, and means under control of the work for disabling said latch means.

6. In a machine for stitching a seam, stitching mechanism operating at regularly recurrent intervals, intermittently acting feeding means tending to move the work forward a predetermined distance between successive stitches, means tending to shorten the stroke of the feeding means, latch means for holding said stroke shortening means out of operative position, and means under control of the work for causing said latch means to move to operative position after the first two stitches of the seam are driven and for withdrawing said latch means after the next to last stitch is driven.

7. In a machine for stitching a seam, stitching mechanism operating at regularly recurrent intervals, intermittently acting feeding means tending to advance the work a predetermined distance between successive stitches, means for shortening the stroke of the feeding means, means functioning once for each stitch driven tending to move said stroke shortening means out of operative position, latch means for holding said stroke shortening means out of operative position, and means under control of the work for setting said latch means after the first feed movement is completed and withdrawing said latch means prior to the last feed movement.
